(57) **CLAIM**

I claim the ornamental design for a mountable control panel, as shown and described.

DESCRIPTION

FIG. 1 is a front perspective view of a mountable control panel showing my new design;

FIG. 2 is a front view thereof;

FIG. 3 is a right side view thereof;

FIG. 4 is a left side view thereof;

FIG. 5 is a bottom end view thereof;

FIG. 6 is a top end view thereof;

FIG. 7 is a front view thereof showing a condition wherein the indicia is illuminated; and,

FIG. 8 is a front view thereof showing a condition wherein the indicia is illuminated and the cover for the control panel is opened.

1 Claim, 6 Drawing Sheets
